UNITED STATES PATENT OFFICE.

DAVID M. HITCH, OF LAUREL, DELAWARE.

DENTAL ARTICULATOR.

SPECIFICATION forming part of Letters Patent No. 530,524, dated December 11, 1894.

Application filed April 5, 1894. Serial No. 506,462. (No model.)

To all whom it may concern:

Be it known that I, DAVID M. HITCH, a citizen of the United States, residing at Laurel, in the county of Sussex and State of Delaware, have invented new and useful Improvements in Dental Articulators, of which the following is a specification.

This invention has for its object to improve and facilitate the use of dental articulators and render susceptible of a wider range of accurate adjustment that type of articulators wherein a pair of jaws or model holders are pivotally connected, and the upper jaw is supported by a ball-and-socket joint.

15 The invention also has for its object to render the ball-and-socket joint of the upper jaw capable of forward and backward, or horizontal adjustment without varying the position of the joint relatively to the heel portion of the upper jaw supported thereby, whereby the joint for the vertical movement of the upper jaw is constantly maintained in close juxtaposition to the heel of the model and at an unvarying distance therefrom, in 20 such manner that while the ball-and-socket joint and the upper jaw or model-holder are adjustable horizontally in unison, the joint constantly lies quite near the heel of the model, whereby it is possible to conveniently 25 compensate for, or remedy the tilting of the wax base plate in obtaining the bite of the patient.

To accomplish the objects specified my invention consists in the features of construction and the combination or arrangement of parts hereinafter described and claimed, reference being made to the accompanying drawings, in which—

Figure 1 is a perspective view of a dental 40 articulator constructed in accordance with my invention; and Fig. 2 is a longitudinal central sectional view of the same.

In order to enable those skilled in the art to make and use my invention, I will now describe the same in detail, referring to the drawings, wherein—

The numerals 1 and 2 indicate the lower and upper jaws or model-holders which are constructed as usual to receive, support, and 45 carry the casts or models of the person's jaws. The lower jaw or base 1 is provided at the rear portions of its sides with inclined stand-

ards or brackets 3 having rearwardly projecting approximately horizontal arms 4, and rigidly connected, near their upper ends, by a connecting tie or cross-bar 5 having at its center a screw-threaded socket 6 with which engages a vertically arranged set-screw 7 having a suitable head 8 at its lower end by which to rotate it, and thus vertically adjust the same in the screw-socket 6.

To the extremities of the arms 4 are pivoted rearwardly projecting arms 9 of a boxing 10, through which extends the shank of two cups 12, which constitute a ball socket. The shank 65 of the cups is composed of two flat plates or bars 13 and 14, arranged one upon the other, and both adapted to slide lengthwise through the boxing 10, for the purpose of adjusting the ball-socket forward or backward, or horizontally.

The heel portion of the upper jaw or model carrier 2 is provided with a centrally arranged ball 15, fitting the cups 12, and adapted to rotate between the same, in such manner that the upper jaw or model carrier can be adjusted in any direction whatever. The ball 15 can be rigidly clamped by the cups 12 to hold the upper jaw or model-holder in a fixed position relatively to the cups through the medium of a set-screw 16 which passes loosely through the shank section or plate 13, and engages a screw-threaded orifice in the shank section or plate 14 at a point between the boxing 10 and the cups 12, so that by 85 turning the set-screw in the proper direction the ball 15 will be gripped or released. The set-screw is in close juxtaposition to the cups, so that it will not interfere with the adjustment of the cups quite near to the boxing. 90 The top wall of the boxing is provided with a screw-threaded socket, through which extends a set screw 17, which, at its inner end, bears against the upper shank section or plate 13, whereby the two shank sections or 95 plates can be rigidly clamped together, and also clamped in a fixed position in the boxing, for the purpose of holding the ball-and-socket joints 12 and 15 in the position to which adjusted.

The arms 9 of the boxing are preferably pivoted to the arms 4 through the medium of a through-pivot pin 18 mounted in the arms 4 and engaging the arms 9, and this pivot-

pin is preferably removable for the purpose of detaching the parts if desired.

The standards or brackets 3 rise above the tie or cross-bar 5, so that the arms 9 of the boxing can pass down between such upward extensions and rest against the tie or cross-bar, thereby producing a nicely finished article.

The pivoted swinging boxing 10 is adapted 10 to rest against the upper end of the set-screw 7, and obviously the elevation of the boxing, and, consequently of the upper jaw or model-holder 2, can be varied to suit the conditions required, by the proper adjustment of the 15 set-screw.

The set-screws 7 and 17 are preferably provided with ordinary lock nuts for securing them in the position to which adjusted.

In my improved construction the ball 15 is 20 directly at the heel of the upper jaw or model-holder 2, and this ball engages a ball-socket carried by a lengthwise adjustable shank composed, as here shown, of two superimposed sections or plates, whereby the ball-and-socket joint can be adjusted forward or 25 backward, or horizontally without in any manner changing the relative position of the joint to the heel of the upper jaw or model-carrier. This is a very desirable and important feature of my invention and avoids or 30 remedies defects which exist in prior articulators having a ball-and-socket-joint.

The pivotal connection of the arms 9, with 35 the arms 4, enables the biting movement of the human jaws to be closely imitated, as in ordinary articulators; while the horizontally adjustable ball-and-socket joint secures the wide range of adjustment of the upper jaw or model-holder which enables the dentist to 40 meet every possible condition likely to arise in manufacturing sets of artificial teeth.

The tie or cross-bar 5 rigidly connects the standards of brackets 3, and thereby braces and strengthens the same, while at the same 45 time the tie or cross-bar carries the set-screw 7, which secures the elevation or depression of the boxing to vary the elevation of the upper jaw or model-holder.

In making artificial teeth, the plaster model 50 is covered with a base plate of wax on which

is placed a rim of wax directly over the ridge. The patient bites on the wax base plate and rim, and if the lower front teeth first touch the wax rim, the heel of the wax base plate is tilted, and I can readily compensate for this, 55 or remedy the same, by having the ball joint directly at the heel of the upper jaw or model-holder.

Having thus described my invention, what I claim is— 60

1. The combination in a dental articulator, of the lower jaw or model-holder having standards provided with a connecting tie-bar, a set-screw extending through said tie-bar, a yoke pivoted to the standards, supported by the 65 upper end of the set-screw and having a central boxing, a pair of cups forming a ball-socket, and having a shank adjustable lengthwise in the boxing, an upper jaw or model-holder having a ball in close juxtaposition to 70 its heel portion and fitting between said cups, and a set-screw passing through the shank of the cups to clamp them on the ball, whereby the ball and socket are adjustable to and fro without varying their relative position with 75 respect to the heel of the upper jaw or model-holder, substantially as described.

2. The combination in a dental articulator, of a lower jaw or model-holder having standards or brackets provided with rearwardly 80 projecting arms, a boxing having side arms pivoted to said rearwardly projecting arms, a pair of superimposed shank sections or plates adjustable lengthwise in the boxing and provided at one end with cups forming 85 a ball-socket, an upper jaw or model-holder having a ball in close juxtaposition to its heel portion and fitting between said cups, a set screw for supporting the boxing at different heights, a set-screw for rigidly clamping the 90 two shank sections together and to the boxing, and a set-screw for clamping the cups on the ball, substantially as described.

In testimony whereof I have hereunto set my hand and affixed my seal in presence of 95 two subscribing witnesses.

DAVID M. HITCH. [L. S.]
